UNITED STATES PATENT OFFICE.

CHARLES P. LYNCH, OF ST. LOUIS, MISSOURI, ASSIGNOR TO ST. LOUIS UNIVERSITY, OF ST. LOUIS, MISSOURI, A CORPORATION OF MISSOURI.

VALVE.

SPECIFICATION forming part of Letters Patent No. 703,963, dated July 1, 1902.

Application filed December 6, 1901. Serial No. 84,935. (No model.)

To all whom it may concern:

Be it known that I, CHARLES P. LYNCH, a citizen of the United States, residing in the city of St. Louis, State of Missouri, have invented 5 a certain new and useful Improvement in Valves, of which the following is a full, clear, and exact description, such as will enable others skilled in the art to which it appertains to make and use the same, reference being had 10 to the accompanying drawings, forming part of this specification, in which—

Figure 1 is a central vertical sectional elevation, certain of the parts being shown in side elevation. Fig. 2 is a view generally 15 similar to Fig. 1, the parts being shown in a different position; and Fig. 3 is a top plan view, partly in section, on the line 33 of Fig. 1.

My invention relates to improvements in valves, and more particularly to valves in 20 which packing is unnecessary, my object being to provide an efficient and convenient structure in which leaking is well guarded against.

To this end and also to improve generally 25 upon devices of the character indicated my invention consists in the various matters hereinafter described and claimed.

Referring now more particularly to the 30 drawings, 1 indicates the globe or main portion of the valve-casing, having the usual seat 2.

3 indicates the extended sleeve portion of 35 the casing, and 4 is the cap for closing the upper end of the same.

5 refers to the valve-stem, provided with the usual hand-wheel 6, and 7 indicates the valve, which is suitably supported upon the lower 40 end of a sleeve 8. Said sleeve is interiorly threaded and is engaged by the lower threaded end 9 of the valve-stem, suitable vertical slots 10 in the periphery of the sleeve receiving guide-wings 11 upon the casing, whereby rotation of the valve-stem serves to raise or 45 lower the valve without rotating the same, and thus grinding it upon its seat.

Near its upper end the valve-stem is provided with an enlargement 12, whose upper surface is rounded and turned to closely fit a seat 13 in the under surface of the cap 4, the

lower portion of said enlargement extending 50 into the bore of the casing portion 3. Immediately below the said enlargement the casing-wall extends inwardly a short distance to produce a shoulder, which lies under the edge of the said projection, and at a suitable point 55 below said shoulder 14 the casing-wall again extends inwardly to produce a shoulder 15, a spring 16 being coiled about the stem and bearing between said shoulder 15 and the under surface of the enlargement 12, whereby 60 said enlargement is held to its seat. At about the point of the valve-stem which lies in line with the shoulder 15 when the parts are assembled said stem is provided with a collar 17, which is of slightly less diameter 65 than the diameter of the coiled spring, whereby said collar does not interfere with the proper seating of the spring upon the shoulder 15, but prevents accidental separation of the spring from the stem when the stem is 70 withdrawn from the casing. For the sake of illustration the space between the shoulder 14 and the under surface of the enlargement 12 is exaggerated. In practice, however, this space is somewhat less than one thirty-second of an inch in a full-sized valve, whereby 75 any considerable depression of the valve-stem by the operator when turning the same is prevented.

As is shown in Fig. 2, the proportions and 80 arrangement of the parts are such that the end of the stem is seated against the end of the sleeve 8 before the said sleeve or the valve engages any portion of the casing. Thus when the valve is fully raised further rotation 85 of the stem in the direction for raising said valve and sleeve is impossible. This is important, for were the upward movement of the sleeve to be arrested before the stem has reached the limit of its movement further rotation of said stem would cause the same to 90 further enter the sleeve, and in so doing the enlargement 12 would be drawn away from its seat 13 against the action of the spring 16, thus permitting leakage through the cap 95 about the stem.

The present construction of valve is simple in its construction and efficient in operation,

the parts being readily made and assembled, excessive depression of the valve-stem being avoided, withdrawal of the enlargement from its seat by the rotary movement of the stem being prevented, and the accidental separation of the spring from the stem when the parts are withdrawn from the casing being guarded against.

5 I am aware that many minor changes in the construction, arrangement, and combination of the several parts of my device can be made and substituted for those herein shown and described without in the least departing from the nature and principle of my invention.

10 Having thus described my invention, what I claim as new, and desire to secure by Letters Patent, is—

15 1. In a valve, a valve-casing, a valve-stem, a cap having a seat in its lower face, an enlargement upon said stem fitting said seat, and a fixed casing portion extending under

said enlargement and adjacent thereto; substantially as described.

2. In a valve, a casing having an inwardly-extending shoulder, a cap having a seat in its lower face, a valve-stem, an enlargement thereon fitting said seat, a spring about said stem and between said shoulder and said enlargement, and a collar upon said stem at substantially the point thereof which lies opposite said shoulder when the parts are assembled, said collar engaging said spring but being of less diameter than the same; substantially as described.

20 In testimony whereof I hereunto affix my signature, in the presence of two witnesses, this 3d day of December, 1901.

CHARLES P. LYNCH.
